UNITED STATES PATENT OFFICE.

ISAAC J. SHIFLEY, OF CHICAGO, ILLINOIS.

MACHINE FOR WORKING SHEET METAL.

No. 909,341.

Specification of Letters Patent.

Patented Jan. 12, 1909.

Application filed June 24, 1907. Serial No. 380,492.

To all whom it may concern:

Be it known that I, ISAAC J. SHIFLEY, a citizen of the United States, residing at Chicago, county of Cook, State of Illinois, have 5 invented a certain new and useful Improvement in Machines for Working Sheet Metal, and declare the following to be a full, clear, and exact description of the same, such as will enable others skilled in the art to which 10 it pertains to make and use the same, reference being had to the accompanying drawings, which form a part of this specification.

My invention relates in general to the art of shaping sheet metal and particularly to a 15 machine for giving to strips of sheet metal any desired configuration and forming thereon a bead or beads.

In my prior patents 759,480, and 803,859, I have disclosed machines of this general 20 character, the particular machines illustrated being adapted to form eaves-troughs with one or both edges beaded and in one of its aspects the present invention may be regarded as consisting of improvements in such 25 prior machine.

The primary object of my invention is to provide means whereby the beads in devices of the character specified may be quickly and easily formed in such a manner that they 30 shall be of uniform size and shape throughout their length.

A further object of my invention is to provide means whereby bead or beads of any desired cross-section may be progressively 35 formed on the sheet metal devices during the shaping of the devices, without danger of failure on the part of the bead forming devices to form a perfect bead.

A further object of my invention is to provide a simple and compact machine which 40 will operate quickly and positively to give to strips of sheet metal any desired shape and provide at one or both edges thereof a bead of any desired configuration.

A further object of my invention is to provide means for progressively forming a strip 45 into a bead or tube of any desired cross-section irrespective of whether the bead or tube is formed as a separate device or as a part of some other device.

Specifically speaking, my invention comprises rolls for shaping a strip of material so as to give it the desired form and at the same time start the bead or beads by bending one

or both of the edges of the strip backwards 55 so as to produce a flange at one or both sides of the strips; together with a second series of rolls which progressively act upon the flange or flanges to produce the bead or beads of the desired configuration. The flanges need not 60 necessarily be formed by the main rolls but this is the most convenient way of forming them. Associated with the second series of rolls is an elongated mandrel, the cross-section of which gradually diminishes so that as 65 the strip of material passes through the machine a flange is progressively formed and is then progressively bent about the mandrel so as to form it into a tube of gradually diminishing diameter. The shape of the 70 bead depends, of course, upon the shape of the smaller end of the mandrel.

My invention will be more fully understood and its various objects and advantages will be more clearly apparent from the following detailed description taken in connection with the accompanying drawings. The various features of novelty which characterize my invention will, however, be herein-after pointed out with particularity in the 80 claims.

In the drawings Figure 1 is a plan view of a machine arranged in accordance with a preferred form of my invention, a part of the machine which may take any usual or 85 preferred form omitted; Fig. 2 is a section taken on line 2—2 Fig. 1 looking in the direction of the arrows; Fig. 3 is a section taken on line 3—3 of Fig. 1 looking in the direction of the arrows and showing only the two 90 coöperating rolls and a strip of material between them; Fig. 4 is a section taken on line 4—4 of Fig. 2; Fig. 5 is a section taken on line 5—5 of Fig. 2; Fig. 6 is a section taken on line 6—6 of Fig. 2; and Figs. 7, 8, and 9 95 are details.

Referring to the drawing, A and A' indicate the side frames of a machine having a base A' of any suitable form. Mounted upon shafts journaled in the members A' 100 and A are groups of rolls B and other groups of rolls C. These rolls are driven in any suitable manner, as by means of driving pulleys D and D' and trains of gearing E. The particular arrangement of supporting these 105 rolls and of driving them forms no part of the present invention and may be varied in any way desired. Each group of rolls B

consists of three similar rolls b' , b^2 , and b^3 or, in other words, the machine is adapted to operate on three strips at a time. Although this is a convenient arrangement, since wide sheets may be run through the machine and cut into strips thereby, it will, of course, be understood that my invention is not confined to machines operating upon a plurality of strips simultaneously; and in describing the present invention reference will be had to only one set of the triplicate mechanisms shown. The rolls B , the mandrels F with which they coöperate, and all of the other parts to the left of these rolls may take any usual or preferred form. The present invention has to do with that portion of the machine to the right of the rolls B , namely with the completion of the trough or other device after it has been partially formed and provided with one or more downwardly projecting flanges at the edges thereof.

In Fig. 3 there is shown the preferred shape of the extreme right hand end of rolls B for use in a machine adapted to form a rough, semi-circular in cross-section and having cylindrical beads at each edge.

G indicates the strip of material which is being operated upon; and, it will be seen, that the edges thereof have been bent downward over the mandrels so as to form depending flanges g . In this condition the strip approaches the second set of rolls C . These rolls are preferably arranged at some distance from the first set of rolls in order that the flanges may be partially formed into beads before the strip reaches the second set of rolls.

The mandrels F may be circular in cross-section until they pass the left hand group of rolls B at which point their cross-section changes, as at F' , so as to have a depth almost equal to the width of the flanges and preferably the same thickness as before. In other words, the cross-section of the mandrels at this point is that of a rectangle with rounded corners. The mandrels then gradually taper toward the right hand end of the machine until at or near the extreme right hand ends they are again circular in cross-section. After passing the last of the rolls B the strip is engaged by small rollers H arranged on vertical axes just outside of the mandrels so that the flanges are pressed firmly against the mandrels. The rollers H are so shaped that they also press upon the material passing across the upper side of the mandrels and at the same time bend the extreme lower edges of the flanges beneath the lower edges of the mandrels. Thus the flanges are partially molded about the mandrels in such a manner that there is no danger of springing or distorting the metal of the trough in any way. This operation is illustrated in Fig. 4.

Immediately following the rollers H are

two groups of rollers I and I' ; these rollers being arranged on horizontal axes, the one above and the other below the mandrel. The depth of the mandrels is slightly less at this point than immediately adjacent the rollers H and therefore the lower ends of the flanges are carried still further beneath the mandrels. The molding of the flanges is effected by the rollers I' , the rollers I serving to hold the material firmly down upon the mandrels and preventing the slipping or springing thereof out of position. The rollers I and I' are preferably arranged as close as practicable to the rollers H in order that the material may be firmly supported adjacent the rollers I and I' . After leaving the rollers I and I' , a further set of rollers H' is reached; these rollers being exactly the same as the rollers H , except that they are shorter on account of the decreasing depth of the mandrels. It will be seen that the rollers H' serve to still further bend the flanges around the lower edges of the mandrels. The next set of rollers to be encountered are the rollers I^2 and I^3 , corresponding to the rollers I and I' , and being exactly similar thereto. The rollers I^2 and I^3 are arranged closer together, however, than the rollers I and I' , because of the decreasing depth of the mandrels and they act to mold the inturned ends of the flanges still further inwardly and upwardly. As the strip continues through the machine it passes other rollers H^2 to H^7 , respectively, corresponding to the rollers H , and I^4 to I^{13} , respectively, corresponding to the rollers I and I' ; the one set of rollers becoming gradually shorter and shorter and the other set gradually approaching each other as the depth of the mandrels diminishes. In Fig. 6 is shown the condition of the trough after passing the rollers H^7 . It will be seen that the flanges have been bent so as to form complete tubes and it will be evident that by increasing the number of the small rollers and varying the size of the ends of the mandrels the process of rolling the metal of the flanges could be still further continued so as to give beads having any desired degree of stiffness. Furthermore, by placing the small rollers near enough together and using sufficiently large numbers thereof, the formation of the beads will be effected smoothly and positively so that all of the beads will be of uniform size and all danger of spoiling a trough on account of an ill-shaped bead will be obviated.

Since the body of the trough has not received its final shape when it leaves the rolls B , the second set of rolls C is provided, these rolls being arranged; however, to act solely upon the body portion of the troughs so as to gradually increase the curvature thereof.

In the machines shown in my aforesaid prior patents these latter rolls are provided with flanges for aiding in the formation of

the beads, but I prefer to form the beads wholly by means of the auxiliary rollers after the troughs have been flanged; and therefore the rolls C need be shaped only so as to engage the body portion of the troughs.

It is, of course, not essential that the flange forming devices be arranged in the exact relation to the two sets of main rolls as indicated in the drawings; but this arrangement 10 is the preferable one, since the machine may be made of a minimum length and at the same time all of the forming devices may perform their functions efficiently without interference with each other.

15 It will now be understood that a blank strip of material is inserted into the machine and as it is drawn along by the various rolls it is partially formed into the desired shape and its edges are progressively folded down 20 over the converging mandrels; thereafter the depending edges are progressively molded into the desired shape and the body portion of the strip is molded and set into the final form in which it emerges from the machine.

25 The small bead-forming rollers need not be driven by power but may be revolubly supported in such relation to the mandrels that the strip, as it is drawn through, causes them to rotate. In order that the proper pressure 30 may be obtained, the rollers are preferably adjustably supported whereby they may be carried toward or away from the mandrels as conditions may require.

A convenient arrangement for supporting 35 the rollers is to provide channel-shaped sub-frames A³, each of which is arranged parallel with and incloses one of the tapered mandrels. The rollers H' to H³ may conveniently be supported in brackets h which are 40 secured in any suitable way to the webs of the members A³. In order that these rollers may be adjusted laterally with respect to the mandrels they are preferably mounted upon shafts such as h' which have at their opposite 45 ends eccentrics h² and h³. These eccentrics fit into circular openings h⁴ and h⁵ in the brackets h so that by rotating the eccentrics the axes of the rollers are shifted laterally with respect to the mandrels. The rollers 50 may be retained in their adjusted positions, by means of set-screws h⁶. The shafts h', together with their eccentric bearings, may be supported from the top flanges a³ of the members A³ by means of bolts h⁷ which are 55 secured at their lower ends to the eccentrics h² and are provided with nuts h⁸ which are arranged above the flanges a³.

The rollers I and the other rollers corresponding thereto may conveniently be supported above the mandrels in hangers i which have stems i' projecting upwardly through the flanges a³. Nuts i¹ and i² which respectively engage the upper and lower sides of the flanges a³ serve to adjust the hangers 65 into any desired position. The hangers are

prevented from rotating by being engaged in slots i⁴ in brackets i⁵ supported from the flanges a³ as clearly shown in Figs. 2 and 5.

The rollers I' and the other rollers corresponding thereto are preferably supported 70 in such a manner that they may not only be adjusted vertically, as are the rollers I, but so that they may be tilted slightly so as to move them within a small angle about the lower edges of the mandrels. To this end each roller may conveniently be supported upon a shaft k which is arranged to be vertically movable within a slot k' in a bracket k¹; the bracket k² being supported from the lower flange a⁴ of the member A³. Two 80 rods, k³ and k⁴, respectively, support the shaft k from the flange a⁴. One of these rods is secured to the end of the shaft opposite to that on which the wheel is mounted; while the other rod passes through an opening k⁵ 85 in the shaft at a point near the wheel. The opening is so arranged that the shaft may rock about a horizontal axis on this rod. It will be seen that the wheel may be vertically adjusted by adjusting the nuts k⁶ and k⁷ on 90 the upper ends of the two rods respectively, by equal amounts. If it is desired to tilt the roller slightly, either of the rods may be adjusted vertically independently of the other, thereby causing the shaft of the roller to be 95 oscillated slightly so as to bring it into any desired position with respect to the lower edge of the corresponding mandrel.

While I have described in detail a preferred construction and arrangement of parts 100 for carrying out my invention, I do not desire to be limited to this particular construction and arrangement, since in its broader aspect my invention contemplates various other mechanisms and devices as will be apparent 105 from the definitions of my invention constituting the appended claims.

Having now fully described my invention, what I claim as new and desire to secure by Letters Patent is:

1. In a machine for forming a trough with a beaded edge, rolls for partially shaping the trough and bending one edge backward so as to form a flange, a tapered mandrel adapted to pass between the body of the trough and the flange, a plurality of rollers distributed lengthwise of and about the mandrel for progressively molding said flange about the mandrel and rolls for completing the shaping of the trough.

2. In a machine for shaping a strip of material and forming a bead at its edge, a plurality of rolls for gradually shaping said strip, a mandrel, means on said rolls for bending one edge of said strip over the mandrel to form a flange, a second mandrel having a progressively decreasing cross-section, and rollers co-operating with said latter mandrel to mold the flange into a bead having a progressively decreasing diameter.

3. In a machine for shaping a strip of metal and forming a bead thereon at one edge, a set of rolls for partially shaping said strip, a mandrel, means on said rolls for bending one edge of said strip over said mandrel to form a flange, a second set of rolls for completing the shaping of said strip, a second mandrel having a gradually decreasing cross-section, and means independent of said second set of rolls for molding said flange progressively about said mandrel as the strip is fed through the machine.
4. In a machine for forming a bead at one edge of a strip of material, means for bending one edge of said strip laterally to form a flange, a mandrel of progressively decreasing cross-section, means for moving said strip along said mandrel, and rollers distributed along and about said mandrel for progressively molding the flange so as to cause it to conform to the shape of the mandrel at various points throughout the length of the mandrel.
5. In a sheet-metal working machine, a tapered mandrel, having its larger end of greater width than thickness, rollers distributed about and along the mandrel, certain of the rollers engaging an edge of the mandrel, and means for adjusting said latter so as to cause them to assume various angular positions with respect to said edge.
6. In a machine for shaping a strip of metal and forming a bead thereon at one edge, a plurality of rolls arranged one in advance of the other for changing the shape of said strip, a tapered mandrel extending along said rolls transversely to the axis thereof, and a plurality of rollers arranged about and along said mandrel for bending the strip about the mandrel as the strip 40 passes through said rolls.
7. In a machine for forming a trough with a beaded edge, a series of rolls arranged one in advance of the other for shaping a strip of metal into a trough, the first rolls of the series being arranged to bend one edge of the strip backward so as to form a flange, a tapered mandrel extending along said rolls transversely to the axis thereof and in position to pass between said flange and the main portion of the strip, and a plurality of rollers distributed along and about the mandrel for progressively molding said flange about the mandrel as the strip is fed through the machine.
8. In a sheet metal-working machine, a tapered mandrel having its larger end of greater depth than thickness, a plurality of rollers distributed along the top edge of said mandrel to hold a strip of metal firmly against the mandrel, a plurality of rollers distributed along one side of the mandrel and arranged to force the strip against that side of the mandrel and bend it progressively around the under side of the mandrel, and a plurality of rollers arranged along the bottom edge of the mandrel for forcing said strip against the mandrel and bending the free edge thereof upwardly along the side of the mandrel and toward the top edge.
- In testimony whereof, I sign this specification in the presence of two witnesses.
- ISAAC J. SHIFLEY.
